COMBINED ASH TRAY AND CIGARETTE EXTINGUISHER

William J. Vaughn, 2338 Highbury St., Los Angeles, Calif.

Filed May 6, 1963, Ser. No. 74,771

Term of patent 14 years

(Cl. D85—2)

Fig. 1

FIGURE 1 is a perspective view of a combined ash tray and cigarette extinguisher, showing my new design; FIGURE 2 is a sectional view taken on line 2—2 of FIGURE 1.

I claim:

The ornamental design for a combined ash tray and cigarette extinguisher, substantially as shown.
